INVENTOR:

John B. Burrell

UNITED STATES PATENT OFFICE.

JOHN B. BURRELL, OF FALL RIVER, MASSACHUSETTS.

SHAFT-TUG.

SPECIFICATION forming part of Letters Patent No. 270,931, dated January 23, 1883.

Application filed May 29, 1882. (No model.)

To all whom it may concern:

Be it known that I, JOHN B. BURRELL, of Fall River, in the county of Bristol, in the State of Massachusetts, have invented a new and useful Improvement in Shaft-Tugs; and I do hereby declare the following to be a specification thereof, reference being had to the accompanying drawings.

Like letters indicate like parts.

10 Figure 1 is a perspective view of my invention. Fig. 2 is a vertical section of the same.

My invention relates to that part of a harness which sustains the weight of the thighs; and it consists of a suitable metallic ring of an 15 ovoid shape, provided with pins and encircled by leather straps confined in place by said pins, and having an external metallic band, clamping the whole together by means of a set screw.

In the drawings, A represents the shaft-tug proper, which is made of any suitable metal, and furnishes the wearing-surface sustaining the weight of the shaft and the friction thereof. It is made preferably in an ovoid shape, as shown in Fig. 2, having the inner or exposed 25 surface rounded and the outer or covered side a plane surface. At the upper or smaller end a transverse groove and central socket are formed to receive the buckle B and its buckle-tongue. The tug A has a series of spurs or

30 points, a a, and a series of pins, b b, which are cast in one piece with said tug. At the larger or lower end of the tug, and cast with it, is a stud, c, fitted with a screw-thread to receive the set-screw C. A box-loop, D, preferably of 35 leather, is attached to the tug A by means of the spurs a entering therein, as shown in Fig. 2. A lining-strap, E, preferably of leather, extends from the box-loop D, encircling the plane edge of the tug A, and held thereon by the pins

40 b b, which pass through corresponding holes in said lining-strap. This strap passes between

the inner end of the buckle and the tug, and is somewhat cut away for that purpose, and has a perforation for the buckle-tongue. This strap, however, simply serves as a lining, and 45 may be omitted without essentially changing my invention. An external leather strap, F, extends from stud c and surrounds the lining-strap E, and is held in place by the pins b b, received through corresponding holes. It is 50 perforated through its central point to allow the insertion of the tongue of the buckle B. The strap F, passing inside the box-loop D, serves to hold it in snug contact with the tug A, and for the purpose of still further stiffening said loop and to prevent its lateral displacement a rectangular piece, d, of sheet metal (indicated in Fig. 2 by a heavy solid line) is inserted between the strap F and the inside surface of the loop D. A metallic band, 55 G, of sheet metal, encircles the external strap F and at its free ends buttons on the stud c. It is also perforated at its central point for the insertion of the tongue of the buckle B. The band G serves to give a finish to the article 60 and to conceal the ends of the pins b b. A metallic strap-loop, H, covers and confines the free ends of the band G, and is fastened in position by the set-screw C, thus holding all the parts firmly together. 70

I claim as a new and useful invention and desire to secure by Letters Patent—

The improved shaft-tug herein described, consisting of the metallic tug A, having spurs a, pins b, and stud c, the buckle B, box-loop D, 75 straps E F, band G, strap-loop H, screw C, and stiffening-piece d, all combined and arranged substantially as specified.

JOHN B. BURRELL.
